UNITED STATES PATENT OFFICE.

WILLIAM G. WALTER, OF PITTSBURG, PENNSYLVANIA, ASSIGNOR TO
CAMPBELL, JONES & CO., OF SAME PLACE.

DESIGN FOR A GLASS VESSEL.

SPECIFICATION forming part of Design No. 16,607, dated April 6, 1886.

Application filed February 15, 1886. Serial No. 192,043. Term of patent 3½ years.

To all whom it may concern:

Be it known that I, WILLIAM G. WALTER, of Pittsburgh, in the county of Allegheny and State of Pennsylvania, have invented a new and useful Design for Glass Vessels; and I do hereby declare the following to be a full, clear, and exact description thereof.

My design consists in a concave glass vessel whose shape or configuration is a representation of a wisp broom or brush. It is shown in the accompanying drawings, in which—

Figure 1 is a plan view of the bottom of a glass vessel, illustrating my design. Fig. 2 is a plan view of the upper or inside of the vessel, illustrating a modification. Fig. 3 is a vertical cross-section on the line $x-x$ of Fig. 1.

Like symbols of reference indicate like parts in each.

As shown in the figures of the drawings, the configuration of the vessel is such as to give it approximately the outline appearance of a wisp-broom.

The form shown in Fig. 1 has superficial longitudinal striations or ridges *a*, representing the fibers of straws of the broom, a handle, *b*, and an intermediate ornamental pattern, *c*.

The vessel shown in Fig. 2 has the contour of a wisp-broom, but is otherwise unfigured.

As wisp-brooms differ from each other in outline or shape, I do not desire to claim the shape or outline of the vessel viewed on a horizontal or other plane; but by the term "configuration" employed in the claims I desire to include vessels which convey to the eye the impression of a representation of a wisp-broom, whatever its outline or shape may be.

I claim—

1. The design for table vessels or dishes herein shown and described, the same consisting in the concave vessel whose configuration is that of a wisp-broom, as set forth.

2. The design for table vessels or dishes herein shown and described, the same consisting in the concave vessel whose configuration is that of a wisp-broom, and which is provided with longitudinal striations representing the straws or fibers of the broom, as set forth.

In testimony whereof I have hereunto set my hand this 13th day of February, A. D. 1886.

WILLIAM G. WALTER.
